UNITED STATES PATENT OFFICE.

WALTER HEILEMANN AND HEINRICH KANONENBERG, OF ESSEN-ON-THE-RUHR, GERMANY, ASSIGNORS TO FRIED. KRUPP AKTIENGESELLSCHAFT, OF ESSEN-ON-THE-RUHR, GERMANY.

WHEELED GUN-CARRIAGE.

1,138,949.

Specification of Letters Patent.

Patented May 11, 1915.

Application filed April 26, 1913. Serial No. 763,846.

To all whom it may concern:

Be it known that we, WALTER HEILEMANN and HEINRICH KANONENBERG, residing at Essen-on-the-Ruhr, Germany, both subjects of the Emperor of Germany, have invented a certain new and useful Improvement in Wheeled Gun-Carriages, of which the following is a specification.

This invention relates to wheeled gun carriages particularly intended as defence against swiftly traveling targets, such for instance as air ships. For the purpose of permitting an easy and rapid turning of gun carriages of this kind, they are provided 10 with for instance a pivot stand. Such a pivot stand *c* consists of two parts, journal and bearing, connected by a vertical pivot, of which the lower part *c*¹ is sunk down into the ground, and the upper part *c*² connected 15 with for instance a pivot stand. Such a pivot stand *c* consists of two parts, journal and bearing, connected by a vertical pivot, of which the lower part *c*¹ is sunk down into the ground, and the upper part *c*² connected 20 with for instance the axle tree *a*² of the trail A, see Fig. 3. The height of the pivot stand is therefore selected so that the wheels will be raised from the ground when the gun carriage has been brought to rest on the stand, 25 whereby the gun carriage together with the upper part of the pivot stand may, without great exertion, be swung around relative to the lower part of the stand which has been inserted into the ground.

30 The present invention relates to a device for a gun carriage of this description which will prevent the digging into the ground of the trail spade, and thereby facilitating the swinging around of the carriage resting on the pivot stand.

The object of this invention is attained by providing the spade with a shoe which may slide on the ground.

One embodiment of this invention is described in the accompanying drawing wherein:

Figure 1 shows a side view partly in section of a trail end with spade and shoe; Fig. 2 a corresponding top plan view partly 45 in section; and Fig. 3 a side view of gun and carriage together with the pivot stand, partly in section and in smaller scale.

The trail end A is provided with a spade B B¹ adjacent its rear end, which is composed of a spade shaped plate B and a pressure plate B¹. In order to prevent the digging into the ground of the spade of the gun carriage connected with the pivot stand, a shoe C is provided, which is constructed as 55 a tray shaped box, open on its upper side.

In the bottom of this box is secured a bearing D for the spade plate B. This bearing is provided with a groove *d*¹ for the deepest part of the knife of the spade and two perpendicular walls *d*² against which the spade 60 may rest with its side edges. Two eyes *d*³ are arranged on the bearing D, between which eyes an arm E is mounted to turn by means of a spindle *d*⁴. This arm E carries a hook *e*¹ at its free end which is adapted to 65 grip a shaft F mounted in a bearing on the trail end A. The shaft F is provided at each end with eccentric trunnions *f*¹ mounted in ears *a*¹.

A flexible lever G is securely fastened on 70 one of the trunnions *f*¹, which lever may be engaged by a dog *a*² situated on one of the trail sides A.

When using the spade shoe the trail end is seated therein with its spade plate B in such 75 a manner that the knife edge engages with the groove *d*¹ of the bearing D, and the side edges of the spade rest against the walls *d*² of the bearing D. The arm E is thereupon laid, with its hook *e*¹ on the shaft F, while 80 the lever G has the position shown by dot and dash lines in Fig. 1; and the spade shoe under coöperation of the shaft F and arm E is then secured on the spade by swinging the lever G into the position shown in full lines. 85 On swinging the gun carriage around the pivot stand *c*, the spade shoe then slides with its bearing surface on the ground.

When it is desired to use the gun carriage as an ordinary traveling carriage, that is 90 without the pivot stand, the spade shoe is detached from the carriage by turning the lever G into the dot and dash line position.

We claim:

1. In a wheeled gun carriage having a 95 spade on the trail end, a tray shaped shoe, means for attaching the shoe beneath the spade, thereby providing a smooth sliding surface for the trail on the ground and a pivoted device for anchoring the gun carriage to the ground, said device allowing an 100 easy training of the gun carriage.

2. In a wheeled gun carriage having a spade on the trail end, a tray shaped shoe, 105 means for attaching the shoe beneath the spade, thereby providing a smooth sliding surface for the trail on the ground; said means comprising a bearing piece having a transverse groove and vertical end walls for securely gripping said shoe and a pivoted 110

- device for anchoring the gun carriage to the ground, said device allowing an easy training of the gun carriage.
3. In a wheeled gun carriage having a spade on the trail end, a tray shaped shoe, and means for attaching the shoe beneath the spade, thereby providing a smooth sliding surface for the trail on the ground; said means comprising a bearing piece having a transverse groove and vertical end walls for securely gripping said shoe; a pair of eyelets on said bearing piece, a spindle secured in said eyelets, an arm mounted to revolve on said spindle provided with a hook at its free end, a transverse shaft and eccentric bearings therefor on the trail, and locking members for securing said shaft in a certain position when said hook is in engagement with said shaft.
- 10 4. In a wheeled gun carriage having a spade on the trail end, a tray shaped shoe, and means for attaching the shoe beneath

the spade, thereby providing a smooth sliding surface for the trail on the ground; said means comprising a bearing piece having a 25 transverse groove and vertical end walls for securely gripping said shoe; a pair of eyelets on said bearing piece, a spindle secured in said eyelets, an arm mounted to revolve on said spindle provided with a hook 30 at its free end, a transverse shaft and eccentric bearings therefor on the trail, a flexible lever at one end of said shaft and a dog on the trail end constructed to secure said lever in a certain position when said hook is 35 in engagement with said shaft, whereby said shoe may be held securely to the trail end.

The foregoing specification signed at Bar-
men, Germany, this 5th day of April, 1913.
